UNITED STATES PATENT OFFICE.

DAVID L. WATSON, OF NEW ORLEANS, LOUISIANA.

CLARIFYING AND FILTERING APPARATUS.

SPECIFICATION forming part of Letters Patent No. 761,187, dated May 31, 1904.

Application filed October 2, 1903. Serial No. 176,474. (No model.)

To all whom it may concern:

Be it known that I, DAVID L. WATSON, a citizen of the United States, residing at New Orleans, in the parish of Orleans and State of Louisiana, have invented new and useful Improvements in Clarifying and Filtering Apparatus, of which the following is a specification.

My invention pertains to water-filters; and it consists in the novel and advantageous water clarifier and filter hereinafter described, and particularly pointed in the claims appended.

In the accompanying drawings, forming part of this specification, Figure 1 is a broken view, partly in vertical section and partly in elevation, of the apparatus constituting one embodiment of my invention. Fig. 2 is a plan of the apparatus with the covers of the casing and the several compartments therein removed. Fig. 3 is a broken plan view of one of the electrolyzers of the apparatus removed. Fig. 4 is a transverse section of the same. Fig. 5 is a plan view of one compartment of the apparatus, illustrating another and preferred type of electrolyzer therein. Fig. 6 is a vertical section of the same. Fig. 7 is an elevation of one of the electrodes of the preferred electrolyzer removed, and Fig. 8 is an elevation illustrating the disposition of the electrodes of the electrolyzer with respect to the partition thereof.

Referring by letter to said drawings, and more particularly to Figs. 1 to 4 thereof, A is the casing of my improved apparatus, which is preferably of sheet metal and is provided with a removable cover *a* and a draw-off cock *b*, and B is a false bottom arranged in the casing and serving, in conjunction with the bottom thereof, to form a chamber *C*, designed for the reception of the foreign substances removed from the water. The said chamber is provided, as shown in Fig. 1, with a valved pipe *c*, through which it may be readily discharged of the collected foreign substance when desired.

D, E, F, and G are compartments, preferably cylindrical, arranged in the casing A and having removable covers *d*. The compartments D, E, and F have bottoms *e*, which

are pitched or inclined downwardly toward the centers thereof and are connected at such points, through the medium of pipes *f*, with the chamber C. This is in order to enable them to discharge sediment into said chamber. The compartment D is also provided, as best shown in Fig. 1, with a diametrical partition *g*, which extends from its upper end to a point adjacent to its bottom *e* for a purpose presently described.

H, H are electrolyzers arranged on suitable supports in the compartment D at opposite sides of the partition *g* and dividing said compartment into upper and lower portions. These electrolyzers respectively comprise a horizontal frame *h*, of marble or other suitable material, having grooves *i* in the inner sides of its side bars; plates *j*, of platinum or other suitable material, seated in the said grooves *i* and each having a projection *k* at one end; a conductor *l*, connected to the projections *k* of the alternate plates and designed to be connected with the positive pole of an electro-generator, (not shown,) and a conductor *m*, connected to the projections *k* of the other plates and designed to be connected with the negative pole of the electrogenerator.

I is a water-supply pipe leading from a source of supply to the compartment D at a point above the electrolyzers; J, a port or pipe connecting the compartments D and E at a point above the electrolyzers; K, a filtering-body, preferably composed of charcoal, sand, and quartz, arranged in a holder L in the compartment E at a point above the connection J; M, a port or pipe connecting the compartments E and F at a point above the filtering-body K; N, a filtering-body, preferably of stone, arranged in a holder P in the compartment F at a point above the connection M, and Q a port connecting the compartment F at a point above the filtering-body N and the casing A, which latter is designed to contain the clarified and filtered water, as shown.

In the practical operation of my improved apparatus water enters the compartment D through the pipe I and passes downwardly in said compartment at one side of the partition *g*. Incident to such downward passage of the water it is subjected, through the medium of

one of the electrolyzers H, to the direct action of a current of electricity, which coagulates the foreign substance and clarifies the water. The foreign substance settles to the 5 bottom of the compartment D, while the water passes upwardly in said compartment at the opposite side of the partition g and through the other electrolyzer H, through the medium of which it is again subjected to the direct action 10 of the current of electricity for the purpose stated. From the compartment D the water passes through pipe J into the compartment E. In said compartment E the water passes upwardly through the filtering-body 15 K, while the foreign substance settles to the bottom of the compartment. The water passes from the compartment E at a point above the filtering-body K through the pipe M and into the compartment F, and it then 20 passes through the filtering-body N and the pipe Q into the casing A. Any foreign substance that may remain in the water precedent to the passage thereof through the filter-body N will be separated from the water by 25 said body and settle to the bottom of the compartment.

From the foregoing it follows that when the water reaches the casing A it will be thoroughly clarified and filtered; also, that the foreign 30 substance separated from the water will settle to the bottom of the compartments D, E, and F and immediately pass from thence into the chamber C. This latter is materially 35 advantageous, since it reduces to a minimum the liability of deposited foreign substance being again taken up by the water during the passage of the same through the compartments D, E, and F.

The compartment G is designed to contain 40 ice or any other agent suitable for cooling the filtered water in the casing A.

The electrolyzer H' (shown in Figs. 5 to 8 of the drawings) is the one which I prefer to employ. This electrolyzer H' is arranged in 45 the compartment D below a partition g', which depends from the top of the compartment, and it comprises a frame h', of marble or other suitable material, plates or electrodes j', of platinum or other suitable material, and 50 insulating-slabs j''. The frame h' is made up of a vertical partition p, which is connected to and depends from the partition g' and is provided in its opposite sides with vertical grooves r, intermediate walls h² of less height 55 than the wall p, arranged parallel to said wall p and having vertical transverse slots and also having vertical grooves in their inner sides above and below and in communication with the said slots, side walls s of a less 60 height than the walls h², arranged parallel to said walls h², and side walls t, disposed at right angles to the walls p, h², and s and connecting the same. The plates or electrodes j' are arranged between the walls p and h² of the 65 frame, with their vertical edges in the grooves

of said walls, and are provided with projections k, which extend through the slots or openings in the walls h² into the chambers h³, formed between the walls h² and the walls s. The insulating-slabs j'' are disposed above and 70 below the electrodes and between the walls p and h² of the frame and in the grooves of the said walls. The projections k of the alternate electrodes j' of the two series shown are connected to conductors l, which rest in the 75 chambers h³ and are designed to be electrically connected with the positive pole of an electrogenerator, (not shown,) and the projections k of the other electrodes of the two series are connected to conductors m, also disposed in the chambers h³ and designed to be connected with the negative pole of the electrogenerator. The electrolyzer as a whole is hermetically sealed with wax or other suitable material, and from this it follows that in 80 passing through the electrolyzer liquid must take between opposing faces of the electrodes. It will also be observed that the electrodes are insulated on all sides, and in consequence water in passing between the faces of the electrodes will be thoroughly treated with a current of electric fluid. It will further be noticed that while the water passes between the faces of the electrodes it cannot reach the conductors l and m. 85

When the electrolyzer H' is embraced in my novel apparatus, the water which enters the compartment D through pipe I passes down between the electrodes j' at one side of the partition p and then up between the electrodes 90 at the opposite side of the partition and is in consequence thoroughly treated with electricity. As a result of this electrical treatment the foreign substance in the water is coagulated and settles to the bottom of the compartments D, E, and F, Figs. 1 and 2, so that 95 when the water is discharged into the casing A, as before described, it is thoroughly clarified and purified. 100

I have entered into a detailed description of the construction and relative arrangement of the parts embraced in the present and preferred embodiments of my invention in order to impart a full, clear, and exact understanding of the same. I do not desire, however, to 110 be understood as confining myself to such specific construction and relative arrangement of parts, as such changes or modifications may be made in practice as fairly fall within the scope 115 of my invention as claimed. 120

Having described my invention, what I claim, and desire to secure by Letters Patent, is—

1. A water clarifying and filtering apparatus, comprising a compartment having a bottom, inclined downwardly to its center, an electrolyzer arranged in said compartment, a water-supply pipe connected with the compartment, a second compartment connected with the first-mentioned compartment, at the oppo- 125 130

site side of the electrolyzer with reference to the water-supply pipe, and having a discharge, and also having a bottom inclined downwardly to its center, a filtering-body arranged in the 5 second-mentioned compartment between the water inlet and discharge thereof, and a chamber arranged below and connected to the centers of the bottoms of the compartments, and having a valved discharge.

10 2. A water clarifying and filtering apparatus, comprising a compartment, an upright partition arranged in said compartment and extending from the upper end to a point adjacent to the bottom thereof, electrodes arranged 15 in said compartment, at opposite sides of the partition, a water-supply pipe connected with the compartment, above one set of electrodes, a second compartment connected with the first-mentioned compartment, at a 20 point above the other set of electrodes, and having a discharge, and a filtering-body arranged in the second-mentioned compartment between the water inlet and discharge thereof.

3. A water clarifying and filtering apparatus, comprising a compartment, an upright partition arranged in said compartment and extending from the upper end to a point adjacent to the bottom thereof, electrodes arranged 25 in said compartment, at opposite sides of the partition, a water-supply pipe connected with the compartment, above one set of electrodes, a second compartment connected with the first-mentioned compartment, at a 30 point above the other set of electrodes, and having a discharge; a filtering-body, of charcoal, sand and quartz, arranged in the second-mentioned compartment between the water inlet and discharge thereof, a third compartment connected with the discharge of the second-mentioned compartment, and having a 35 discharge of its own, a filtering-body, of stone, arranged in the third compartment, between the inlet and discharge thereof, a casing containing the several compartments, and adapt-

ed to receive filtered water from the third- 45 mentioned compartment, and a chamber, at the bottom of the casing, connected with the bottoms of the several compartments, and having a valved discharge.

4. In a filtering and clarifying apparatus, 50 the combination of a compartment having an inlet and an outlet, and an electrolyzer arranged in the compartment, and comprising a vertical partition disposed between the inlet and the outlet, and sets of insulated electrodes 55 disposed at opposite sides of the partition.

5. In a filtering and clarifying apparatus, the combination of a compartment having an inlet and an outlet, and an electrolyzer arranged 60 in the compartment, and comprising a frame of insulating material having a vertical partition disposed between the inlet and the outlet, sets of electrodes disposed in the frame at opposite sides of the partition, and slabs of insulating material arranged in the 65 frame above and below the electrodes.

6. In a filtering and clarifying apparatus, the combination of a compartment having an inlet and an outlet, and an electrolyzer arranged 70 in the compartment, and comprising a frame of insulating material having a vertical partition disposed between the inlet and the outlet, and also having chambers at opposite sides of the partition, slabs of insulating material arranged in the frame between the partition and the chambers and having projections extending into the latter, slabs of insulating material arranged in the frame above and below the electrodes, and conductors arranged 75 in the chambers and connected to the 80 projections of the electrodes.

In testimony whereof I have hereunto set my hand in presence of two subscribing witnesses.
